UNITED STATES PATENT OFFICE.

JAMES C. ANDERSON, OF JERSEY CITY, NEW JERSEY, ASSIGNOR TO VARLEY DUPLEX MAGNET COMPANY, A CORPORATION OF NEW JERSEY.

MACHINE FOR COVERING FLAT WIRE.

SPECIFICATION forming part of Letters Patent No. 748,911, dated January 5, 1904.

Application filed April 30, 1903. Serial No. 154,921. (No model.)

To all whom it may concern:

Be it known that I, JAMES C. ANDERSON, a citizen of the United States, residing at Jersey City, in the county of Hudson and State of New Jersey, have invented certain new and useful Improvements in Machines for Covering Flat Wire, of which the following is a full, clear, and exact description.

This invention is a machine for insulating or covering electrical conductors, more particularly for covering conductors of flat or ribbon form.

The machine consists, essentially, of rolls and folding-dies for first forming the insulating material, which is in the form of a strip of suitable fabric, into a closed envelop, in combination with devices for opening the envelop, inserting the flat wire, and thereafter closing the envelop upon the wire.

This machine will now be described in detail with reference to the accompanying drawings, in which—

Figure 1 is a sectional view through the various rolls, parts being broken away, while other parts are shown in elevation. Fig. 2 shows five different sectional views of the folding-die. Figs. 3, 4, 5, and 6 are cross-sections of portions of the various rolls through which the material passes, and Fig. 7 is a perspective view illustrating a portion of the operation of the machine.

x indicates a strip of paper or other suitable fabric destined to cover or insulate the wire, the flat wire being indicated by *y*. The strip *x* is somewhat wider than the flat wire, being substantially twice the width thereof, so that it may nearly cover the metal when it is folded around it. Both strips are supposed to lead from a reel to the covering-machine illustrated. At the front of the machine is a pair of rolls *a* *a'*. The upper roll is provided with a smooth periphery flanked on each edge by flanges *a*², which just admit the strip *x*. Roll *a'* is provided with two annular ridges *a*³, located at equal distances from the edges and separated by a space substantially equal to the width of the wire. The two rolls are connected together by gearing *a*⁴, and the lower roll is hung at the free end of one or more crank-arms *a*⁵, acted upon by a spring *a*⁶, in order to press the lower roll constantly

against the upper roll. *b* and *b'* are another pair of rolls, similarly geared together and mounted to create pressure between them. The abutting surfaces of these rolls are smooth, as indicated in Fig. 4. Both of the rolls *a* and *b* are driven from the main gear *c*, to which power is applied in any suitable manner. In line with the contact-points of both pairs of rolls and between them is arranged a folding-die, consisting of two main parts *e* and *f*, so arranged with respect to each other as to form an elongated passage-way through which the strip *x* is to pass. The shape of this passage-way gradually changes from one end to the other, as indicated by Fig. 2, which shows sections of the die taken at the five different points 1, 2, 3, 4, and 5. Beyond the rolls *b* and *b'* is arranged a table *g*, above which is hung a guide-sheave *h* for the flat wire *y*. Between the table and the sheave is a space partially occupied by two triangular wedge-shaped blocks *i* and *j*. The apex of block *i* points forward, while that of block *j* points rearward. The lower surface of each block is substantially parallel to the surface of the table *g* and slightly above it, so that the paper strip can pass under the blocks. The adjoining ends of the blocks are separated to permit the wire *y* to pass tangentially from the sheave *h* beneath the block *j*. At the rear of the machine are mounted two other rolls *k* and *k'*, which are pressed toward each other by a mounting similar to those previously described.

The operation of the machine is as follows: The strip of paper or other material for insulating or covering the wire is first led through the rolls *a* and *a'*, where two lines of scoring are formed on its under side, the fiber of the paper being sufficiently crushed or cut to form lines upon which the strip may be afterward folded. From the rolls *a* *a'* the strip leads into and through the folding-die *e* *f*. Here the lateral edges of the strip are gradually bent upward to the right-angular position shown at section 3 of Fig. 2 and then folded inward and downward toward the body of the strip, as shown in section 5 of Fig. 5. Then emerging from the die the folded strip leads onward to the two plain pressure-rollers *b* and *b'*, which press or iron the folds

and "fixes" or "sets" them. The strip then leads between the triangular block *i* and the table *g*, the body of the strip passing under the block, while the folded edges are lifted 5 into a right-angular position by the nose of the block. Leading on in this shape the open strip or envelop is presented to the space between the two blocks, where the wire *y* can then pass into the space between the raised 10 edges of the strip and accompany the strip in its passage beneath the block *j*. Leaving the block *j* the natural tendency of the edges of the strip to fold downward is exerted, and the wire is thus covered. Immediately, however, 15 the covered wire passes between the final pressing-rolls *k* and *k'*, where the strip is again set to more firmly embrace the wire. The covered wire finally leads to a suitable storing-reel *l*. In this operation it will be 20 seen that the closed envelop is first formed with a seam extending longitudinally, after which the envelop is opened and the wire inserted, and finally the envelop is closed upon the wire.

25 Having described my invention, I claim—

1. In a machine for covering or insulating flat wire, the combination of means for folding the lateral edges of a strip into a closed envelop, means for opening the envelop longitudinally, means for inserting the wire in the open envelop and means for thereafter closing the envelop, substantially as described.
2. In a machine for covering or insulating 35 wire, the combination of means for folding

the lateral edges of a strip of covering material and means for thereafter inserting a wire beneath the folds of the strip, substantially as described.

3. In a machine for covering or insulating 40 flat wire, the combination of a folding-die adapted to fold the lateral edges of a strip of covering material, a device for opening said folds and means for inserting the wire beneath the open folds and again closing the folds. 45

4. In a machine for covering or insulating flat wire, the combination of means for longitudinally scoring the strip of covering material, a die adapted to fold the strip along the scored lines, triangular blocks adapted to 50 pass under and between the folds to open them, a guide adapted to direct the wire beneath the open folds and means for finally folding the strip upon the wire.

5. In a machine for covering or insulating 55 flat wire, the combination of a pair of rolls, one of which is provided with ridges adapted to longitudinally score the covering-strip, a die adapted to fold the strip along the scored lines, another pair of rolls adapted to press 60 the folded strip and means for opening the folds and inserting the wire in the strip, substantially as described.

In witness whereof I subscribe my signature in presence of two witnesses.

JAMES C. ANDERSON.
